UNITED STATES PATENT OFFICE.

MIRANDA R. S. DAVIS, OF KANSAS CITY, ASSIGNOR OF ONE-FOURTH OF HER RIGHT TO JAMES P. HOWE, OF MACON, MISSOURI.

IMPROVEMENT IN HOOKS AND EYES.

Specification forming part of Letters Patent No. 123,619, dated February 13, 1872.

To all whom it may concern:

Be it known that I, Mrs. MIRANDA R. S. DAVIS, of Kansas City, in the county of Jackson and State of Missouri, have invented a new and useful Improvement in Hooks and Eyes; and I do hereby declare that the following is a full, clear, and exact description thereof, which will enable others skilled in the art to make and use the same, reference being had to the accompanying drawing forming part of this specification.

This invention relates to a new and useful improvement in hooks and eyes for fastening dresses or clothing, and for all purposes to which hooks and eyes are applicable; and it consists in the mode of fastening the hooks and eyes to the cloth or other material hereinafter shown and described.

In the accompanying drawing, Figure 1 is a view of an eye before it is inserted. Fig. 2 shows it inserted ready for fastening. Figs. 3 and 4 show the eye fastened in the cloth, two modes being shown of fastening. Figs. 5, 6, and 7 show the hook inserted. Figs. 8, 9, and 10 show it fastened in the cloth.

Similar letters of reference indicate corresponding parts.

My hooks and eyes are formed with two pointed shanks, which allows them to be in-

serted in the cloth the same as pins, as represented in the drawing, and when inserted they are fastened either by bending the shanks over and down onto the cloth, as seen in Fig. 3, or bending over the eye or hook, as seen in Figs. 4, 9, and 10.

A is the eye; B, the hook; C represents the shanks, and D the crook in the shanks. E is the material to which the hooks and eyes are attached.

It will be seen that no needle and thread are required. The improved hooks and eyes may be inserted and fastened almost as easy as common pins can be inserted, and in the most substantial and perfect manner.

Having thus described my invention, what I claim as new, and desire to secure by Letters Patent, is—

A hook or eye, having two sharp-pointed shanks C, crooked at the points D to form shoulders, as described, so that by forcing them through the fabric up to and against the said shoulders, and then bending the ends they are firmly secured.

MIRANDA R. S. DAVIS.
